(57) CLAIM

The ornamental design for a malt house, as shown and described.

DESCRIPTION

Fig. 1.1 is a front view of an embodiment of a malt house showing my new design;

Fig. 1.2 is a perspective view thereof;

Fig. 1.3 is a bottom view thereof;

Fig. 1.4 is a top view thereof;

Fig. 1.5 is a left view thereof; and

Fig. 1.6 is a right view thereof.

The broken lines shown in the drawings depict portions of the malt house that form no part of the claimed design.
